UNITED STATES PATENT OFFICE

2,023,171

REEL

Ralph B. Hayward, La Grange, Ill.

Application April 1, 1933, Serial No. 664,014

1 Claim. (Cl. 242—77)

My invention relates more particularly to disk-like sheet metal structures as for example and more especially those forming the heads of reels provided for the winding thereon of electric cable or the like.

5 My primary object is to provide a construction of the character above referred to which while presenting the desired strength, stiffness and durability may be manufactured at less cost and 10 be of lighter weight than such structures as hitherto provided; and other objects as will be manifest from the following description.

Referring to the accompanying drawings:

Figure 1 is a view in elevation of a reel embodying my invention.

Figure 2 is an end view of the reel with a portion thereof broken away to disclose a detail of construction.

Figure 3 is an enlarged broken longitudinal sectional view of the reel, the section being taken at the line 3—3 on Fig. 2 and viewed in the direction of the arrows.

Figure 4 is a fragmentary sectional view taken at the line 4—4 on Fig. 2 and viewed in the direction of the arrows; and

Figure 5, a similar view taken at the line 5—5 on Fig. 2 and viewed in the direction of the arrows.

Referring to the particular illustrated embodiment of my invention, the reel as shown comprises a hub portion 6 shown as formed of a sheet metal drum with its ends inwardly deflected to form annular flanges 7, and sheet metal heads 8 positioned at the ends of the hub 6 and secured thereto as hereinafter described.

Each head 8 is formed of spaced apart disk-like sheet metal members 9 and 10 centrally apertured as represented at 11 and 12, respectively, to receive an arbor tube 13 secured in place as for example by welding these parts together as indicated at 14 and 15.

The member 9 is shown as formed of a substantially flat sheet metal disk which, in the reel construction, constitutes the inner face of the head.

The member 10 comprises an annular series of sheet metal segments 16 secured together as hereinafter described and forming in effect a sectional disk.

50 Interposed between the members 9 and 10 are reinforcing ribs 17 which radiate from the central axis of the head, these ribs being of wedge shape as shown in Fig. 3, tapering toward their outer extremities and engaging at their opposite longitudinal edges with the members 9 and 10 and

in effect forming braces, the head structure thus formed being of general flat cone form as illustrated.

The ribs 17 in the particular construction shown are formed integrally with the segments 16, being provided as flanges extending inwardly along the radially disposed edges of the segments. Preferably, and as shown, the flange along one edge of each segment and represented at 18 is doubled back as represented at 19 to present an outwardly facing channel or groove 20 into which the flange on the other edge of the adjacent segment and represented at 21, extends, whereby each rib 17 is formed of three thicknesses of metal imparting thereto great resistance to crushing.

25 The members 9 and 10 and hub 6 are secured together by tie rods shown as bolts 22 which extend through openings 23 and 24 in the flanges 7 and the disk 9, respectively, and openings in the 20 segments 16; the heads and nuts provided on these bolts at their opposite ends engaging with the outer members 10, respectively, of the heads 8, as illustrated of the nut 25 in Figs. 3 and 5, to effect the desired clamping action.

It is desirable that the heads and nuts on the bolts 22 be inset relative to the plane of the outer surfaces of the members 10 to avoid undesirable projections thereon, and to this end the portions of the members 10 at which these head-forming parts of the bolts engage, are formed of embossed washers 26 set into openings 27 in the segments 16 and lapping, at peripheral flanges 28 thereon, the walls of the openings 27 to which they are secured as by welding them thereto as indicated at 29.

30 The washers 26 are so positioned relative to the ribs 17, as shown, that portions of the flanges 28 of the washers lap the joints between adjacent segments 16 and thus extend over the outer 40 edges of the ribs, whereby the stiffness of the ribs 17 is availed of in resisting the stresses produced in the tightened condition of the bolts 22.

Reels of this character are commonly rolled 45 along the floor and to provide desirable tread surfaces at the peripheries of the heads I preferably curl the peripheral portions of the disks 9 around reinforcing metal rings 30, as represented at 31, with the peripheral portions of the segments 16 50 interposed between portions of the rings 30 and the disks 9, and the curled portions 31 and the peripheral edges of the segments 16 tack-welded together as indicated at 32.

55 As will be understood from the foregoing, the

heads 8 while being of comparatively light weight are highly resistant to the various stresses to which they may be subjected in use tending to distort them, the ribs 17 serving as compression members resisting stresses tending to deflect the peripheral portions of the head outwardly and as tension members resisting stresses tending to deflect these portions of the head inwardly.

10 While I have illustrated and described a particular construction embodying my invention, I do not wish to be understood as intending to limit it thereto as the same may be variously modified and altered without departing from the spirit 15 of my invention. Thus, by way of example, the reinforcing ribs may be omitted, in which case the member 10, of general conical shape, would

preferably be formed either of a single sheet of metal or of sections connected together.

What I claim as new, and desire to secure by Letters Patent, is:

A reel comprising a hub member, heads at 5 the ends of said hub member, said heads being formed of spaced apart members and ribs interposed between said spaced apart members, the outer ones of said spaced apart members containing openings, embossed washers in said openings and having flange portions which extend crosswise of adjacent ribs and overlap the outer edges of the latter, and tie rods connecting together said hub member and heads and extending into said washers and having head portions located in said washers. 10 15

RALPH B. HAYWARD.
